DEVICE FOR PRODUCING FOAM

Erich Waldschmidt, Berlin-Charlottenburg, Germany, assignor, by means assignments, to Pyrene-Minimax Corporation, a corporation of Delaware

Application January 22, 1934, Serial No. 707,808
In Germany January 20, 1933

4 Claims. (Cl. 261—76)

This invention relates to a device for creating and conducting foam in a mechanical manner. In one device of this kind, air with a certain amount of pressure in very fine streams, is led into a liquid capable of forming foam. In another the gas and the foam-forming liquid are introduced into a device in which an intensive turbulent mixture of these substances takes place creating the foam. This process requires the use of machinery and a considerable consumption of power.

In another process the material which is mixed with another material produces a suction effect by which the latter is sucked in. This process operates at a comparatively low pressure, so that the production of the foam begins in the mixing chamber or just beyond it. Therefore the conducting conduit for the foam mixture must have a large cross-section in view of the high frictional coefficient of the foam, which in the case of long conduits, greatly influences the cost of the apparatus and the installation.

In accordance with another process, pumps are used which suck in the air and the foam-forming fluid and mix them in a mixing apparatus. In this case also, machines having a high power consumption are necessary. Furthermore since the formation of the foam takes place in the mixing apparatus the conducting conduits associated therewith also require large cross-sections.

In applying the present invention, condensed gas or liquefied gas, for instance, carbon dioxide, is used, stored in the well known steel-bottles as a source of gas and energy. Even when requiring the production of very considerable quantities of foam, only a few such bottles with condensed or liquefied gas are necessary.

To extinguish, for instance, the conflagration of an oil-tank of about 30 m. diameter about 100,000 liters of foam would be required. To adhere to the cited example of the carbon dioxide, the required quantity of gas would be only 6 bottles, each of a capacity of 30 kilos contents. An injector-like device may be used, for instance, for mixing the gas with the other ingredients for the foam-formation introducing the gas through a spray-nozzle. The other substance, such as water and the concentrated solution of a foam-former, such as, for instance, Saponin or a diluted foam-solution is either drawn in by the gas or liquid-spray or is introduced under pressure.

The gas escaping from the bottles may be passed through a pipe, for instance, a pipe-coil or similar element, placed within a liquid, which may be

the foam-forming liquid itself, for complete evaporation or pre-heating.

Condensed or liquefied gases have a very high pressure. Therefore the mixture and conducting of the foam-forming substances towards the place of fire can be arranged in pipes under high pressure, resulting, from a point of economy, in the very great advantage of permitting piping of rather small diameter to be used, because the gas and liquid mixture at the existent high pressure 10 remains in its characteristic liquefied condition and consequently has a correspondingly low frictional coefficient. Previous to the flowing of the foam to the place of fire a certain release of the pressure of the gas and liquid mixture takes 15 place, and thus the formation of the foam is effected, for instance, by a widening of the piping at or near its end. It is of particular advantage when using carbonic acid that this gas is absorbed strongly by water when under high pressure, thus 20 resulting in a considerable reduction of volume. For the foam-formation, or its improvement, it is already known to employ suitably porous bodies, such as, for instance, cylindrical receptacles with 25 insets of fibrous fabrics, wire-screens, Raschig-rings or the like, which may be arranged at the beginning of the foam-conduit—at the injector—as well as at the other end, at the place of consumption, or both, at the beginning and at the end.

The accompanying drawing represents a diagrammatic view, partly in section, one form of device in accordance with the invention.

a is a pressure-proof steel-bottle, provided with a discharge pipe b. The branch-pipe c leads tangentially into a cylindrical receptacle d, serving as vaporizer or pre-heater. The tangential introduction of the pipe c into this receptacle has the purpose of throwing by centrifugal force against the wall of the receptacle any snow which might form, in order to effect an evaporation thereof at this point. From the bottom of this receptacle d leads a pipe e, the entrance-opening of which is situated at some distance from the bottom of the receptacle, in order to prevent any clogging up of the pipe by carbon dioxide snow which may have formed here. In place of the receptacle d a pipe-coil might be also used or in order to insure a complete evaporation of the liquefied gas; the latter may be allowed to enter from below into a receptacle partly filled with water.

The exit-pipe e of the vaporizer leads to the injector f which has at its rear end a flange g for the connection of a water-pipe. The water may 55

be brought to the injector under pressure or it may be drawn in by the injector. At the discharge end, the injector is provided with a flange *h* for connecting the foam piping. The latter 5 may contain, as above mentioned, a distributing element at the beginning or at the end, or at both points. A concentrated foam-forming solution, which is mixed within the injector-chamber *l* with the water entering the same, reaches the 10 injector through a pipe *i* coming from the receptacle *k*. A pipe *m* branches off from the pipe *e* and this pipe *m* leads to the top-part of the receptacle *k* for the foam-forming solution. This conduit is provided with a reduction-valve *n*, preventing an excess of pressure within the receptacle *k*. All the pressures prevailing in the receptacles *d* and *k*, as well as in the injector-chamber *l* and at the injector-exit, can be indicated at special gauges *M¹*, *M²*, *M³* and *M⁴*. 15

Having thus described my said invention, what I claim to be protected by Letters Patent is:

1. In an apparatus of the class described, a container for a highly compressed gas, a vaporizing receptacle connected with said container for vaporizing the compressed gas, a container for a foam-forming solution, an injector-like mixing chamber for said gas under pressure and said solution, a conduit for the vaporized gas extending between said vaporizing receptacle and said mixing chamber, said conduit ending within said mixing chamber before its outlet, connections from said container for the foam-forming solution to said conduit and to said mixing chamber, and a discharge conduit extending from 20 said mixing chamber at or near the outlet whereof said mixture expands for the formation of foam.

25

30

35

2. In an apparatus of the class described, a container for a highly compressed gas, a vaporizing receptacle connected with said container for vaporizing the compressed gas, a container for a foam-forming solution, a mixing chamber 5 for said gas under pressure and said solution, a conduit for the vaporized gas extending between said vaporizing receptacle and said mixing chamber, a connection from the upper part of said container to said conduit, a reducing valve in 10 said connection, a connection from the lower part of said container to said mixing chamber, and a discharge conduit connected with said mixing chamber wherein said mixture expands for the formation of foam. 15

3. In an apparatus of the class described, a receptacle for a highly compressed gas adapted to serve as a source of gas and energy, a container for a foam-forming ingredient, an injector device for mixing said gas and foam-form ingredient, a conduit for said gas extending into the forward end of said injector device near the exhaust end thereof, an inlet for water in the rear part of said injector device, a supply pipe extending from said container for the foam-forming ingredient and opening into said injector device between said gas and water inlets, and a pipe leading from the exhaust end of said injector device adapted to convey the mixture therefrom for expansion at suitable points and the production 20 of foam thereat. 25

4. The combination claimed in claim 3 wherein the conduit for the gas extends into the forward end of said injector device and directs the 30 gas through the exhaust end thereof. 35
